DRIVE HEAD FOR DRIVING PIPES

Filed Jan. 28, 1928

FIG. - 1. *Charles C. Hansen*
INVENTOR.
BY *Herbert Gladwin*
L HIS ATTORNEY

UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

DRIVE HEAD FOR DRIVING PIPES

Application filed January 28, 1928. Serial No. 250,288.

This invention relates to rock drills, but more particularly to a driving head adapted to be disposed on the end of a rock drill for guiding a pipe during the driving thereof through the strata overlying the material intended to be drilled.

The objects of the invention are to obviate the necessity of removing loose soil or overburden overlying the rock and to maintain the drill hole clean until it has been charged.

Other objects will be in part obvious and in part pointed out hereinafter.

In the drawings accompanying the specification and in which similar reference characters refer to similar parts,

Figure 1 is an elevation of a drill wagon and a rock drill illustrating a practical application of the invention, and

Figure 2 is a sectional elevation of the drive head and the pipe.

Referring more particularly to the drawings, A designates a drill wagon on which is mounted a vertical frame B. The frame B has a pair of guide members C on which is slidably disposed a rock drill D. The rock drill D in this instance is secured to a carriage E mounted slidably on the guide members C.

Suitable means are provided for raising and lowering the rock drill D on the guide members C. These means comprise a motor hoist F which may be mounted on the drill wagon A to wind up or pay out a cable G attached at one end to the hoist F and with its other end to the carriage E. Near the top of the guide members C is arranged a sheave H which the cable G overruns and whereby said cable is maintained centrally between the guide members C.

In accordance with the present invention, means are provided for driving a drill pipe J through the loose soil K to seat on the material to be drilled, such as rock L. The means provided for this purpose consists of a block O which may be of any suitable ex-

terior formation and has a recess P in one end to receive the end of a front head Q of the rock drill D. The recess P may be of any suitable depth and is preferably of a diameter only slightly larger than that of the front head Q.

In the opposite end of the block O is formed a recess R to receive the end of the pipe J. The end of the pipe J which extends into the recess R may be provided with exterior threads S to receive a sleeve or collar T threaded thereon for the purpose of reinforcing the end of the pipe.

Any suitable means may be provided for clamping the block O to the pipe J. In the present instance a set screw U is threaded into the block O to bear against the collar T for that purpose.

The pipe J may be of a diameter to accommodate the particular size drill bit which it is desired to use and of a length to project above the soil or overburden K after the pipe has been driven against the rock L.

Preferably the front end of the pipe J is provided with a knife-edge V to facilitate the passage of the pipe through the soil K. This knife-edge may be formed either by tapering the pipe on the inside or on the outside. By tapering the pipe on the inside, however, as illustrated, the material displaced by the pipe will be directed more readily into the interior of the pipe and the pipe will also encounter less friction than would be the case if the knife-edge U were formed in line with the inner surface of the pipe.

The recesses P and R are connected by a hole W of sufficiently larger cross sectional area than a drill steel X which extends therethrough to enable the cuttings which rise in the pipe J to pass through the hole W to a plurality of radial apertures Y in the block O through which such cuttings are expelled from the pipe.

The drill steel X may be of a well known type which extends into and is guided by the

front head Q. To obtain the best results, however, the bit Z should be of only slightly smaller diameter than the interior of the pipe J so that the front end of the pipe may be held in alignment with the rock drill by the drill steel and the length of the steel X should slightly exceed that of the pipe.

In practice, whenever it is desired to drive a pipe J into the soil K, a pipe J of suitable length may be inserted in the recess R and clamped to the block O by means of the set screw U. The drill steel X may then be inserted in the pipe J and the assembly is then in readiness to be disposed in operative position with respect to the rock drill D. After the drill steel X has been inserted in the front head Q, the rock drill may be lowered so that the front end of the rock drill will enter the recess P.

The rock drill D may then be set in operation and the hoist F released to permit the entire weight of the rock drill D to bear against the block O. The weight of the rock drill, together with the vibration set up therein, will drive the pipe J into and through the soil K until its front end bears against the rock L. Inasmuch that the cutting bit Z of the drill steel projects slightly in advance of the front end of the pipe J, substantially all the soil in advance of the pipe will be displaced by the bit. Such soil will be raised through the pipe into the hole W and will then pass to the exterior of the block through the apertures Y. As will be readily seen, the drill bit Z will remove substantially all the material so that only a slight amount requires to be displaced by the pipe J.

After the pipe J has been driven into the soil K to the required depth, the set screw may be unscrewed and the rock drill and block removed, leaving the pipe J in the soil K for the succeeding operation of drilling the rock L, as well as for charging the drill hole.

By permitting the pipe J to remain in the soil K, the drill hole will remain clean and the deposit of soil into the drill hole will be prevented.

The present invention is particularly advantageous when used in operations where the mixture of the loose soil with the rock intended to be blasted is not objectionable and in many instances eliminates the unnecessary expense of removing the overburden in order to gain access to the underlying strata.

I claim:

In combination with a rock drill and a drill steel adapted to be actuated thereby, of a drive head having a recess in one end to receive the end of the rock drill, a recess in the other end of the drive head, a pipe encircling the drill steel and extending into the last said recess, said pipe being guided at its free end by the drill steel and having a knife edge on its free end to direct the material

intended to be displaced into the pipe, said drive head having a hole connecting the recesses and through which the drill steel extends, radial apertures in the drive head leading from the hole to the atmosphere for conveying cuttings from the pipe and the block, and means for clamping the drive head to the pipe.

In testimony whereof I have signed this specification.

CHARLES C. HANSEN.
